United States Patent Office

Des. 184,306
Patented Jan. 27, 1959

184,306

PORTABLE BLENDER OR SIMILAR ARTICLE

Angelo C. De Angelis, New Shrewsbury, N. J., and Gerald Stahl, New York, N. Y., assignors to Standard
Electronics Corporation, Newark, N. J., a corporation of Delaware

Application April 9, 1958, Serial No. 50,412

Term of patent 14 years

(Cl. D89—1)

FIG. 1.

FIG. 2.

Fig. 1 is a side elevational view of a portable blender or similar article showing our new design;

Fig. 2 is a top view thereof;

Fig. 3 is a rear elevational view thereof; and

Fig. 4 is a front elevational view thereof.

We claim:

An ornamental design for a portable blender or similar article, as shown.
